UNITED STATES · PATENT OFFICE.

CHARLES J. MILLER, OF MINNEAPOLIS, MINNESOTA.

PARCEL-CARRIER ATTACHMENT.

SPECIFICATION forming part of Letters Patent No. 654,015, dated July 17, 1900.

Application filed April 12, 1900. Serial No. 12,548. (No model.)

To all whom it may concern:

Be it known that I, CHARLES J. MILLER, a citizen of the United States, residing at Minneapolis, in the county of Hennepin and State 5 of Minnesota, have invented certain new and useful Improvements in Parcel-Carrier Attachments; and I do declare the following to be a full, clear, and exact description of the invention, such as will enable others skilled 10 in the art to which it appertains to make and use the same.

My invention relates to parcel or package carrier systems employed in store-service, and has for its object the provision of means 15 adapted to prevent oscillation of the basket or carrier as it arrives at the station and to take up the impetus and impact of the basket or carrier, so as to minimize the strain upon the wires, fixtures, and cars, prevent the crystallization of the wires caused by such oscillation, and consequently effectuate a material 20 saving of wear, thereby greatly lengthening the life of such wires, fixtures, cars, &c., and also by preventing such oscillation permit the 25 immediate lowering of the basket or carrier upon its arrival at the station without requiring the operator to wait, as has heretofore been necessary, for such oscillation to cease, thereby acquiring more speedy service and 30 also preventing the falling of the baskets or carriers by being detached at the station by the operator before oscillation ceases.

My object is to provide such means in the most simple, cheap, compact, and efficient 35 form and in such form as to be readily applied to carrier systems already installed.

To these ends my invention consists in the provision in connection with the station-frame of means whereby as the car arrives at the 40 station and is there stopped all oscillation of the basket or carrier is prevented, the impetus or momentum of the basket being taken up by the yielding character of said means.

More specifically the invention consists in 45 the combination, with the station, of yielding means whereby the basket or carrier is stopped and its impetus and impact taken up.

More specifically the invention consists in 50 the combination, with the station, of yielding means in connection therewith in position to come in contact with the basket or carrier whereby the basket or carrier is stopped and

its impact taken up, relieving all strain from the wires and fixtures.

The invention consists, further, in the constructions and combinations of elements hereinafter described, and particularly pointed out in the claims.

In the accompanying drawings, Figure 1 is a side elevation of my improved parcel or package carrier in the position to be sent out, and Fig. 2 is a view in perspective of my improved carrier attachment detached from its station.

Referring by numerals to the accompanying drawings, 1 designates the sending-out station of the parcel or package carrier, and 2 is the carrier, mounted on the track in the ordinary manner.

3 3 are spools or short sleeves secured to 70 the steel rods 4 4, near the upper ends of the latter, said sleeves or spools 3 3 when in place at the carrier-station being slipped upon studs projecting from the station-frame 6. The lower ends of the steel rods 4 4 are connected to the opposite vertical edges of a plate 6, which is preferably rectangular in 75 form and serves as a buffer or bumper for the basket 7 of the carrier.

8 8 are steel rods, which are connected at 80 their lower ends with the edges of the plate 6 at substantially the same place as the rods 4 4 enter said plate 6. Near their upper ends the rods 8 8 have collars 9 9 secured thereto by set-screws, and immediately above said 85 collars 9 9 the steel rods 8 8 are encircled by spiral springs 10 10, the upper ends of which abut against a cross-head 11, having holes 12 12 in its arms to receive the upper ends of 90 said steel rods 8 8, the projecting upper ends of said steel rods 8 8 being provided with collars 13 13 for retaining said cross-head 11 therebetween. When the attachment is in place, the spools are slipped upon studs projecting from the carrier-frame and the cross-head 11 95 fitting over the rear projecting end of the carrier-frame.

The buffer or bumper is pivoted at a point above its center, so that it normally hangs in a perpendicular position. It is adapted, however, to adjust itself to the form of the end of the carrier or basket, so that whether the end of the basket is perpendicular or inclined the force of the impact of the basket or carrier

against the bumper is distributed evenly over the end of the carrier or basket, lessening the force of the blow by such equal distribution, and thus avoiding unequal strain on any 5 particular part of the basket.

Among the advantages of the above construction is that it takes away all strain from the wires, fixtures, and car occasioned by the oscillation (which is very severe in many 10 cases) back and forth of the basket and contents, the "buffer" or "bumper" receiving such strain at a minimum of wear and tear. Moreover, it prevents the failure to catch caused by the recoil of the car out from under the catch and greatly reduces the wear 15 and strain on the car-catch springs. It prevents breakage of the basket-rods connecting with the basket and basket-bails, prevents all strain on the car-fork springs, and prevents 20 the basket being lowered into or against the cord-handle, thus preventing breakage of baskets.

Various changes in the form, proportion, and the minor details of construction may be 25 resorted to without departing from the principle or sacrificing any of the advantages of this invention.

Having thus fully described my invention, what I claim, and desire to secure by Letters 30 Patent of the United States, is—

1. In a parcel-carrier attachment, the combination with the station-frame, of a bumper or buffer plate; the front connecting-rod; the rear connecting-rod; and a cross-head on 35 the upper ends of said rear connecting-rod, substantially as specified.

2. In a parcel-carrier attachment, the combination with a station-frame, of a bumper or buffer located below the station-frame and 40 connected therewith by flexible rods, and connected with a supporting cross-head supported by the station-frame by flexible rods provided with encircling springs, substantially as specified.

45 3. In a parcel-carrier attachment, a yielding suspending device pendent from the sta-

tion-frame, a movable buffer or bumper carried thereby to receive the impact of the carrier, and means for limiting the movement of said parts and restoring same to their normal position, substantially as set forth. 50

4. In a parcel-carrier attachment, the combination with the station-frame and basket or carrier, of a bumper or buffer pendent from the station-frame and yieldingly supported in 55 position to come in contact with the basket or carrier and whereby said basket or carrier is stopped and its impetus and impact taken up, substantially as set forth.

5. A parcel-carrier attachment, comprising 60 a suspending device to hang pendent from the station-frame, a bumper or buffer carried thereby to receive the direct impact and impetus of the basket or carrier, and means in connection with said bumper or buffer whereby the impetus and impact of said basket or carrier are taken up and oscillation thereof prevented, substantially as set forth. 65

6. A parcel-carrier attachment, comprising 70 one or more front flexible connecting-rods pendent from the station-frame, a bumper or buffer plate carried thereby to receive the direct impact of the basket or carrier, one or more yielding rear connecting-rods also pendent from the station-frame, and one or more 75 springs coöoperating with said rear connecting-rods, substantially as set forth.

7. A parcel-carrier attachment, comprising suspending means, a bumper or buffer plate pivoted thereto to receive the direct impact 80 of the basket or carrier, and spring-pressed means coöoperating with said plate whereby the impetus and impact of the basket or carrier are taken up and oscillation thereof prevented, substantially as set forth. 85

In testimony whereof I have hereunto set my hand in presence of two subscribing witnesses.

CHARLES J. MILLER.
